UNITED STATES PATENT OFFICE.

EDWARD M. DAVIES, OF ALLEGHENY, PENNSYLVANIA, ASSIGNOR OF ONE-HALF HIS RIGHT TO FRANCIS J. REBECK, OF SAME PLACE.

IMPROVEMENT IN CURTAIN-FIXTURES.

Specification forming part of Letters Patent No. 146,659, dated January 20, 1874; application filed October 4, 1873.

To all whom it may concern:

Be it known that I, EDWARD M. DAVIES, of Allegheny, in the county of Allegheny and State of Pennsylvania, have invented a new and Improved Curtain-Fixture, of which the following is a specification:

In the accompanying drawing, Figure 1 represents a front view of a curtain with my improved fixture attached, and Fig. 2 represents a vertical central section of the same.

Similar letters of reference indicate corresponding parts.

The invention will first be fully described, and then pointed out in the claim.

In the drawing, A represents the curtain; B, the roller; C, the flanged wheel or cap attached to the ends of the same. The trunnion or axle *a* of wheel or cap C is extended suitably beyond the hangers or brackets D, in which the roller turns, provided at its outer end with a screw-thread, and produced with square or triangular cross-section. A metallic, rubber, or other spring, E, is placed between washers *b*, either inside or outside of bracket D, as desired. The washer *b* adjacent to bracket D is provided with a round hole in the center, while the other washer *b* has a square or triangular hole to fit on trunnion *a*, and prevent

spring E from getting worn. A check-nut, F, binds washers and spring together, and is prevented, by its washer *b'*, from becoming unscrewed by the pressure of the spring E when the curtain is rolled or unrolled.

The check-nut F is used to regulate the tension of the spring on the bracket, so that the curtain A is held in place in any position in case the cord should stretch, break, or get off the roller.

The attachment may be used at either end only for ordinary curtains, or at both for very heavy ones. The attachment retains, also, the roller securely in the brackets, obviating thereby the annoying detaching of the same, and tearing of the curtain.

Having thus described my invention, I claim as new and desire to secure by Letters Patent—

The combination, with the cap C provided with the axle *a*, of the nut F, washers *b* *b'*, springs E, and bracket D, as and for the purpose described.

EDWARD M. DAVIES.
